BRAKE MECHANISM

John Sneed, Ferndale, Mich., assignor to The Midland Steel Products Company, Cleveland, Ohio, a corporation of Ohio

Application June 18, 1928, Serial No. 286,155

2 Claims.

(Cl. 188—78)

This invention relates to brakes and more particularly to a device for actuating the brake along with the shoe construction and arrangement of cooperating parts.

5 It is among the objects of my invention to provide a device for spreading the ends of a full floating brake shoe apart while either of the ends remains in a fixed position. A further object is to arrange a spreading mechanism which may 10 be journalled in a fixed bearing but which will deliver force and motion in either of two directions. A further object is to arrange thrust parts for transmitting the spreading force to the shoe. Another object is to provide a full floating shoe 15 anchorable adjacent the expanding device and adjustably positioned within the brake drum. A further object is to arrange a shoe cooperable with the expanding device to form a self-energizing brake with parts arranged to prevent grabbing.

20 Other objects include the provision of suitable retractor springs, adjusting shoe positioning means which will appear from the following description of a preferred form of my invention, 25 reference being had to the accompanying drawings. The essential characteristics are summarized in the claims.

Fig. 1 is a partially broken elevation of the 30 brake assembly including the expanding device; Fig. 2 is a section taken along the line 2—2 of Fig. 1; Fig. 3 is a section taken along the line 3—3 of Fig. 1, and Fig. 4 illustrates a modified 35 form of the expanding device.

Referring particularly to Fig. 1, I show a brake 40 having a drum D and an apron or backing plate A which carries an anchor pin P. A full floating shoe S comprising a relatively flexible band-like part 1 welded to a relatively rigid channeled part 2 as at 3, anchors at either end along arcuate 45 anchor engaging surfaces 4 and 5. The channel part of the shoe may be of substantially uniform depth and comprise the "served" part of the shoe when the drum rotates counter-clockwise, as indicated. Suitable brake lining L is carried by the shoe. A separate thrust member 10 is adjustably secured to the flexible end of the shoe in a retaining member 11 by such means as a clamp bolt 12, as described in my copending application Serial No. 281,062 filed May 28th, 1928. The 50 thrust member 10 and the channel end of the shoe carry laterally extending pins 13 and 14, see also Fig. 3, against which the expanding device acts.

Referring also to Fig. 1, the shoe is centered 55 within the drum and retracted from engagement

therewith by retractor springs 15 and 16, which draw the ends of the shoe onto the anchor. The spring 16 may be stronger so that in the usual application of the brake when the drum is rotating counter-clockwise, the band-like end of the 5 shoe is first thrust into engagement with the drum.

An adjustable eccentric stop 17 engages the end of the channel section of the shoe adjacent the joint with the band-like section and a spring 18 draws the channel part of the shoe against the adjustable stop and holds it there in idle position. The spring 18 has one end connected to the outer side flange of the channel part as at 19 and has its other end connected to the apron as 15 at 20 so that the mid-portion of the whole shoe is drawn against the apron. The apron has raised portions as at 21 and 22 which are spaced apart and which support the mid-portion of the shoe at spaced points and hold the body of the shoe 20 away from the apron. Referring also to Fig. 3, it will be seen that the springs 15 and 16 extend at an angle to the apron and tend to draw the ends of the shoe toward the apron. The ends of the shoe are spaced from the apron by the ends of the pins 13 and 14 which contact with the apron 25 as at 23.

Having described a preferred form of the general brake structure and arrangement, I will now describe the expanding mechanism, reference being had particularly to Figs. 1 and 3. Journalled in the apron and in a bracket B is a shaft 30 to which is pinned or clamped an arm 31. The arm 31 may be connected with means not shown for rotating the shaft by any one of the several well known means. To operate the expanding device the shaft is rotated clockwise as viewed in Fig. 1. The shaft may be held against longitudinal movement between a shoulder 32 and the end of the arm 31. Integrally formed or otherwise secured 35 to the shaft is an enlarged head 33 which, near its ends, carries pins 34 and 35. Pivotally mounted on these pins are arms 40 and 41 which arms are interconnected through gearing as at 42. The arm 40 engages the pin 13 which is carried by the member 10 at one end of the shoe, and the arm 41 engages the pin 14 which is carried by the flanges of the channel at the other end of the shoe. Rotation of the shaft 30 in a clockwise direction moves the pins 34 and 35 clockwise 45 and tends to spread the arms 40 and 41.

If the rotation of the drum be counter-clockwise the channel end of the shoe will be held against the anchor by the braking torque, and it is my desire that all of the motion from the 50 55

expanding device be delivered to the band-like end of the shoe. Thus when the shaft 30 is turned clockwise, the upper end of the arm 41 has its travel limited by the relatively fixed position of the pin 14. However, the pins 34 and 35 moving clockwise cause the lower end of the arm 40 to be moved to the left, as viewed in Fig. 1, by reason of the gearing 42, a distance proportionate to the rotation of the shaft, thus moving the free end of the shoe into engagement with the drum.

When the drum is rotating in the reverse direction, then the pin 13 will be held in relatively fixed position by the braking torque and clockwise rotation of the shaft 30 will cause the arm 41 to move the pin 14 and force the other end of the shoe into engagement with the drum.

As appears in Fig. 1, the pin 14 is at a higher elevation than the pin 13 and it may be observed that in the usual application of the brake when the vehicle moves forwardly, that the arm 40 exerts a force which has an upwardly acting vertical component which tends to raise the free end of the shoe into engagement with the drum as well as move it away from the anchor pin.

In Fig. 4 is illustrated a modified form of my invention wherein the arms 40A and 41A correspond to the arms 40 and 41 and may be pivoted about pins 34A and 35A. In this modification instead of gearing the arms together, they are formed to contact with each other along contacting surfaces as at 42A and react upon each other in a like manner. Force and motion are delivered to pins 13A and 14A with substantially the same effect as if the arms were geared together.

It will appear from the foregoing that I have provided a complete brake and expansion device for operating the brake shoe, which will force either end of the shoe into engagement with the drum while the other end of the shoe is held in

contact with the anchor. Various modifications may occur to those skilled in the art all within the major precepts of my invention but I do not care to be limited to the particular form of my invention illustrated and described herewith, or in any manner, other than by the claims appended hereto.

I claim:

1. An expanding device for a brake having friction parts and adapted to deliver compressive forces in opposite directions and move in at least one direction, said device comprising a rotatable member having arms pivoted at its ends, said arms carrying interfitting gear segments meshing substantially in line with the points of pivotal mounting, said arms extended parallel and in opposite directions from the said points and engaging the friction part of the brake at their ends, the point of engagement of each of said arms being substantially at the same elevation as the points of pivotal mounting for the other of said arms whereby rotation of said member moves at least one of said friction parts.

2. An expanding device for a brake shoe adapted to deliver compressive forces in opposite directions and move in at least one direction, said device comprising a member rotatable about a fixed axis and having arms pivoted at its ends, said arms carrying interfitting gear segments meshing substantially in line with the points of pivotal mounting, said arms extending parallel and in opposite directions from the said points and engaging adjacent ends of the brake shoe at the ends of the arms, the point of engagement of one of said arms being below the said axis whereby rotation of said member causes the end of that arm to raise the adjacent end of the shoe as it moves that end of the shoe into engagement with the drum.

JOHN SNEED. 40
